UNITED STATES PATENT OFFICE.

WILLIAM GIERTH AND FREDERICK PETERS, OF NEWARK, NEW JERSEY.

ELECTRIC-LIGHT HANGER.

SPECIFICATION forming part of Letters Patent No. 623,363, dated April 18, 1899.

Application filed October 13, 1898. Serial No. 693,375. (No model.)

To all whom it may concern:

Be it known that we, WILLIAM GIERTH and FREDERICK PETERS, citizens of the United States, residing at Newark, in the county of 5 Essex and State of New Jersey, have invented certain new and useful Improvements in Electric-Light Hangers; and we do hereby declare the following to be a full, clear, and exact description of the invention, such as will 10 enable others skilled in the art to which it appertains to make and use the same, reference being had to the accompanying drawings, and to letters of reference marked thereon, which form a part of this specification.

15 This invention relates to improvements in suspending electric lamps such as are commonly hung over the street upon an arm projecting from a pole and are lowered and raised from time to time for cleaning and renewal of the carbons. Such lowering and raising has usually been done by means of a 20 rope to the end of which the lamp is attached, said rope running through pulleys to a point convenient of access from the ground and always 25 sustaining the full weight of the lamp. This is objectionable in that if the rope becomes weak or broken at any point the lamp will fall to the ground, entailing loss from breakage.

30 The objects of this invention are to provide means which shall support the lamp and carry its weight independent of the rope when said lamp is in normal or elevated position, to provide such a device which will not interfere with or in any way impede raising and lowering the lamp by the rope as usual, to provide means for automatically catching and releasing the lamp, to do this without the use of levers or springs and by a construction 35 simple and not liable to break or get out of order, and to secure other advantages and results some of which may be referred to hereinafter in connection with the description of the working parts.

40 The invention consists in the improved electric-light hanger and in the arrangements and combinations of parts of the same, all substantially as will be hereinafter set forth and finally embraced in the clauses of the claim.

45 Referring to the accompanying drawings, in which like letters of reference indicate

corresponding parts in each of the several views, Figure 1 is a rear elevation of our improved device. Fig. 2 is a central section taken on line *x*, Fig. 6. Fig. 3 is a view from 55 the inside of the hanger-box of a certain detachable front wall or cover, and Fig. 4 is a section of the same on line *y*, Fig. 3. Fig. 5 is a detail view of one of the sections of the suspending-link, and Fig. 6 is a side elevation 60 showing the hanger in use in connection with a pole and lamp of ordinary construction.

In said drawings, *a* indicates an arm which projects from the electric-light pole, as is common; *b*, is the hanger-box or female member of the device; *c*, is the suspending-link or male member, adapted to enter at its upper end the hanger-box and be caught therein, and *d* is an electric lamp of any usual construction attached to the lower end of said 70 suspending-link *c*. Said hanger-box *b* is open at its bottom to admit the suspending-link and at the top has a reduced extension *b'*, in which a pulley *e* for the rope *h* is pivoted on a pin *e'*. Above the said pulley-chamber 75 *b* is a horizontal integral sleeve *f*, adapted to slide on the arm *a* and be secured in any desired position thereon by the set-screw *f'*.

The suspending-link *c* comprises a body portion *c'*, preferably cylindrical and having 80 an approximately spherical upper end *g* and a flattened and perforated lower end *g'*. Said link is centrally and longitudinally bored out from the spherical end *g* through the body portion *c'* to the flattened end *g'*, the tubular cavity thus formed serving to receive the end of the rope *h*.

To enable the end of the rope to be placed in the centrally-bored link, said link is made in two similar halves or sections *ll*, held firmly 90 together by screws *k* near each end, and being at the spherical end *g*, which is preferably hollow for the sake of lightness, provided with lugs *l' l'*, which prevent any lateral displacement or slipping of the sections upon 95 one another. The inner or grooved surface of each section *l* is provided with spurs *j*, those on one section preferably alternating in position with those on the other, said spurs being adapted to enter the rope *h* when the sections are forced together. The screw *k* at the 100 spherical end of the link passes through the

rope and further aids in firmly fastening said rope.

The lamp *d* is attached to the lower end of the suspending-link by means of a hook or wire passed through the perforation therein, and the rope *h*, secured at its end to said link, passes up through the hanger-box *b*, over the pulley *e*, and along the arm *a* in the usual manner.

10 The hanger-box *b* is of slightly-greater thickness in a direction parallel to the arm *a* than the diameter of the spherical head *g* of the suspending-link, and upon the front and rear walls of the box are peculiarly-shaped rests 15 *n n*, adapted to engage said spherical head in a manner to be more fully described. Said rests are each centrally disposed with reference to the width of the hanger-box *b*, thus lying vertically beneath the arm *a*, and each 20 rest comprises a rib or ridge projecting from the wall a half-inch, more or less. This rib may be and preferably is formed integral with the wall, from which it projects; but the rests may be separate pieces fastened to the wall 25 in any suitable manner. The rib thus formed on the wall is approximately semicircular or crescent-shaped and is arranged on the wall in a tilted or oblique position, so that the rest has a hook shape in side view, as will be more 30 clearly understood upon referring to Figs. 3 and 4 of the drawings. At all points of its length said rib projects the same distance from the wall of the hanger-box; but in a direction parallel to said wall the rib is thicker 35 at or near its middle part and tapers toward each end to form arms *p q*, convexly curved outward. The said thickened middle portion of the rib is on the convex side of the rib brought to a point *o*, at which point the convexly curved outer sides of the arms meet. Said point *o* lies at or near the lower edge of the hanger-box at one side of the vertical line 40 passing through the supporting-arm *a*, and the arms *p q* of the rest extend obliquely upward across the said vertical line, the upper arm *p* being longer than the lower *q*. The inner sides of the arms *p q* are concavely curved at a greater degree of curvature than the outer sides and are rounded together 45 where they meet to form a seat or recess *r*, adapted to fit the spherical head *g* of the suspending-link. The position of said rests is such that the center of said spherical head as it lies in the recess *r* will be vertically beneath the supporting-arm *a*, as will be understood.

In drawing the lamp up to its place by means of the rope *h* the head of the hanger strikes the inclined outer sides of the lower 50 arms *q q* of the rests *n n* and is thereby forced to one side until it passes the extremities *q'* of said arms. Then gravity causes the lamp to swing back into a vertical line, throwing the head *g* into the recess *r* of the rests fitted 55 to receive it, and thus the lamp is supported independent of the rope *h*, as will be understood.

To lower the lamp, the rope is drawn upon, and this lifts the head *g* from the recess *r* into contact with the inner sides of the upper arms 70 *p p*, whereby it is guided laterally outward to pass around the ends *p' p'* of said arms, when gravity again brings the lamp and its rope into a vertical line. Now if the rope is slackened the head *g* will strike the inclined outer 75 sides of the arms *p p* and be guided thereby entirely past the rests *n n* on the opposite side from that on which it was drawn up and the lamp may be lowered as usual.

The hanger-box *b* is made of sufficient width 80 to allow the head *g* to pass either side of the rests *n n*, between said rests and the sides of the box.

One wall of the hanger-box, preferably the front one, as *t*, is cast in a separate piece, so 85 as to serve as a door or cover permitting access to the interior, said cover being fastened in place by lugs *s* and screws *s'*. Strengthening-ribs *t'* may be cast upon said removable cover *t*. At points just below the sleeve *f* 90 ears *v v* are provided at opposite sides of the hanger-box, which may serve as means for attaching guy ropes or wires *v' v'*, running to the main pole and steadyng the hanger and arm *a* against oscillation. We also prefer to 95 form on the top of the sleeve *f* upwardly-projecting parallel lugs *w w*, providing a space between adapted to receive the end of a rigid rod or brace *m*, if desired, said end being perforated and secured in place by a pin *i* and 100 the rod *m*, extending upward to the pole from which the arm *a* projects.

Other modifications of minor details may be made without departing from the spirit and scope of the invention, and we do not wish to 105 be limited by the positive terms employed in the foregoing description excepting as the state of the art may require.

Having thus described the invention, what we claim as new is—

1. An electric-light hanger, comprising a hanger-box having an open bottom and inwardly-projecting ribs formed on the two opposite sides in a hook shape, and a suspending-link having an approximately spherical 115 enlarged end engaging said ribs at its opposite sides, substantially as set forth.

2. In an electric-light hanger, the combination of a hanger-box having an open bottom and ribs on two opposite interior walls, each 120 of said ribs being approximately crescent-shaped in side view with arms curving convexly apart, and a suspending-link having an enlarged end circular in cross-section and adapted to engage at opposite lateral points 125 said ribs, substantially as set forth.

3. In an electric-light hanger, the combination of a hanger-box having ribs projecting toward each other from its opposite interior walls, said ribs each forming on the wall of 130 the box a hook shape with upper and lower portions convexly curved apart and extending obliquely upward on the wall of the box, and a suspending-link having an approxi-

mately spherical head of greater diameter than the distance between said opposite ribs and engaging said ridges at its opposite sides, substantially as set forth.

5. An electric-light hanger, comprising a hanger-box *b*, having on two opposite interior walls similarly-disposed integral curved ribs each approximately semicircular with an extension on the convex side, a pulley arranged vertically above said ribs, a single supporting-rope passing over said pulley, and a suspending-link attached to said rope and having an approximately spherical enlargement of a diameter greater than the distance between said ribs and a shank small enough to pass therebetween, the lower end of said link being perforated for attaching a lamp, substantially as set forth.

5. In an electric-light hanger, the combination of a hanger-box having an open bottom and approximately crescent-shaped ribs on opposite sides, an integral sleeve at the top for receiving a supporting-arm, and an intermediate pulley-box with a pulley therein, a rope running over said pulley and a suspending-link secured to the end of said rope, said link being perforated at the lower end for attaching the lamp and having an enlarged upper end adapted to engage said ribs, substantially as set forth.

6. In an electric-light hanger the combination of hanger-box *b*, having on two opposite interior walls curved ribs *n*, the ends of which extend obliquely upward in each rib and the center portion is concavely curved on the upper side to form a seat and downwardly extended on the convex side to form a pointed lower part, and a vertical suspending-link

having an enlarged head circular in plan view and adapted to engage at its opposite sides 40 the upper or lower surfaces of said ribs, substantially as set forth.

7. The herein - described electric - light hanger, comprising a hanger-box *b*, having a sleeve to receive the supporting-arm, a pulley-box and pulley below said sleeve, and a lower chamber having an open bottom and detachable side, hook-shaped rests arranged flatwise on two opposite walls, a rope running over said pulley and a suspending-link comprising sections clamped to said rope and having a spherical head of greater diameter than the distance between said rests and a reduced body portion, substantially as set forth.

8. The combination in an electric - light hanger, of a hanger-box having a pulley at the upper part over which a rope runs, said rope, and a vertical suspending-link secured to the end of said rope in line therewith and having an approximately spherical enlarged upper end, and rests arranged on the inner walls of the hanger-box and having their arms curved to guide the link around said rests when the rope is drawn upon, and forming 65 between themselves a recess to receive the head of said link, substantially as set forth.

In testimony that we claim the foregoing we have hereunto set our hands this 17th day of August, 1898.

WILLIAM GIERTH.
FREDERICK PETERS.
